ATTY'S

UNITED STATES PATENT OFFICE.

THOMAS DUNCAN McFARLANE, OF OTTAWA, ONTARIO, CANADA.

REST.

1,363,335.

Specification of Letters Patent. Patented Dec. 28, 1920.

Application filed February 17, 1920. Serial No. 359,441.

To all whom it may concern:

Be it known that I, THOMAS DUNCAN McFARLANE, a subject of the King of Great Britain, a resident of the city of Ottawa, 5 Province of Ontario, Canada, have invented certain new and useful Improvements in Rests, of which the following is a specification.

This invention relates to improvements 10 in rests for books, trays, telephones and the like, and the objects of the invention are to facilitate securing the rest to a bed, chair, table, bookcase or any suitable support so that a book or other article may be held in 15 position, and when a book is so used it may be conveniently read while allowing the reader to rest in bed or in a chair during the period of reading, to facilitate adjusting the rest so that it may be utilized as a 20 support for glasses, cups or the like, to provide means whereby the rest can be adjusted and swung into position relatively to the reader or user or swung outwardly from a bed or chair, so that it will not prevent the 25 reader from lying down or getting out of bed or from rising from the chair.

Further objects are to render the machine 30 light and durable and capable of being secured to a suitable support with a minimum of time and labor, to eliminate as far as practical any undue spring so that it will not be necessary to adjust the rest each time a different book or article is placed thereon, even although the weights of the several 35 books or articles may differ, and generally to simplify the device and render the several parts easily accessible for inspection and repair.

Other objects will be made clear as the 40 specification develops.

For a better understanding of my invention reference is made to the accompanying drawings in which an embodiment of my invention is illustrated.

45 In the drawings:

Figure 1 is a perspective view of the improved rest, as seen when attached to a bed.

Fig. 2 is a side elevation of the rest, as seen when supported from a bed or other 50 suitable support with the arms of the rest arranged in alinement.

Fig. 3 is a plan view of the same.

Fig. 4 is an enlarged detail of the means 55 for pivotally supporting the rest from the arms.

Fig. 5 is an enlarged plan view of the clamping means.

Like characters of reference refer to like parts in the several figures.

In the drawings; A represents a bed and 60 B the improved rest. This rest comprises a plurality of arms 10 and 11 hinged at 12, so that the one arm is capable of being rotated relatively to the other through the major arc of a circle. The arm 10 is hinged at 13 65 to the U-shaped clamping member 14, which is provided on that arm remote from the hinge 13 with a tensioning screw 15.

The tensioning screw 15 carries a plate 16 which engages with a bearer member 17 of 70 wood or other soft material which will not damage the support to which the rest is clamped, and a second bearing member 18 is located within the clamp 14.

The clamping member 14 is designed to 75 embrace a corner post of a bed, chair, arm or back, table leg or the like so that the bearing member 18 engages with the support and on tightening the tensioning screw 15 the bearing member 17 will be forced into frictional engagement with the support and thus clamp the rest B in position.

This arm 11 is hingedly attached at 19 to the socket 20, which carries a pin 21 having an orifice 22 therethrough adapted to 85 frictionally engage with a hinge pin 23 which passes through the hinges 24 of the rest 25. The hinges 24 are frictionally held in position relatively to the pin 23 by thumb screws 26 which are threaded through the 90 hinge 24.

The hinges 24 and the hinge pin 23 have orifices 29 which register and through which the pin 30 is adapted to pass and when the rest 25 is used as a support for glasses and 95 the like, the pins 30 will prevent any tendency of the rest rotating downwardly when stress is applied thereto.

The rest 25 is provided at the lower edge with a flange 27 which will support the 100 lower edge of a book placed thereon thus preventing the book slipping off. The pin 21 is capable of being rotated about its longitudinal axis within the socket 20, and may be retained in any desired position by a 105 thumb screw 28 and thus the rest 25 may be adjusted to any angular position to suit the requirements of the user.

When the rest 25 is used as a support for 110 a tray it is rotated into a horizontal plane

by loosening the set screw 28 and rotating the pin 21 about its longitudinal axis and the set screw is then tightened. The pin 30 is passed through the orifices 29 in the hinge 5 24 and pin 23 and prevents the rest 25 from rotating around the hinge pin.

When the rest is to be used, the clamp 14 is positioned to engage with a suitable support and in the embodiment illustrated em-

10 braces the corner post of the bed as shown in Fig. 1, whereupon the thumb screw 15 is tightened to bring the bearing member 17 into frictional engagement with the post, which is thus held between the two members 15 17 and 18. The rest can now be swung into position with the arm 10 arranged in parallel relation to the sides of the bed, and with the arm 11 extending transversely across the bed.

20 The thumb screw 28 is now loosened and the rest 25 is rotated into an angularly disposed position to allow a book to rest thereon in position to be read, and the thumb screw 28 is then tightened.

25 The reader can now adjust the position of the arms 10 and 11 to better suit his requirements so that he may recline or sit up in bed and read while at the same time resting.

30 It may be necessary to adjust the rest 25 slightly to properly focus the book to suit the requirements of the reader and if this is desirable then the set screws 26 are loosened and the rest 25 rotated around its 35 hinges 24 and hinge pin 23 whereupon the set screws 26 are tightened.

It may be further convenient to convert the rest 25 into a holder for a tray, glasses, cups or the like, and to permit of this being 40 done, the thumb screw 28 will be loosened and the pin 21 rotated to bring the rest 25 into a horizontal position, and the pin 30 is inserted in the orifices 29.

45 A tray containing glasses, may be placed on the rest 25, and it will properly support the same without any tendency of the rest 25 rotating about the hinge pin 23, so that the rest will now function as a small table.

The device may be constructed of any suitable material which will possess great strength and durability and not liable to warp or twist, so that when books are placed on the rest 25 and arranged for reading, there is no necessity for re-adjusting the 55 rest to suit each book, because the primary adjustment will be sufficient.

In the embodiment illustrated, I have

shown a pair of bearing members 17 and 18 having curvilinear inner faces, but of course it will be understood these will be shaped to 60 suit the support with which they are to engage which need not necessarily be a bed post, but any other article of furniture giving adequate support to the rest can be used, so that the book rest is also adapted for use 65 on chairs, etc.

From the above description it will be seen that I have invented a rest which may be utilized for a number of purposes such as supporting a book when reading, supporting 70 trays, or other articles, telephone stand, sheet music stand, the several parts of the rest being simple in construction and not liable to go out of repair.

When using the rest for books, etc., elastic 75 bands may be utilized and passed around the rest to engage the covers and so hold the book in position.

As many changes could be made in the above construction and many widely different embodiments of my invention within the scope of the claims, constructed without departing from the spirit or scope thereof, it is intended that all matter contained in the accompanying specification and drawings 85 shall be interpreted as illustrative and not in a limiting sense.

What I claim as my invention is:

1. A rest of the class described comprising a clamping member, hinged arms supported 90 by the clamping member, a socket supported by an arm, a pin rotatably mounted in the socket, means for retaining the pin in position, a hinge pin carried by the last said pins, a rest having hinges engaging the 95 hinge pin, and pin means passing through the hinges and the hinge pin.

2. A rest of the class described comprising a clamping member, an arm hinged to the clamping member, a second arm hinged to 100 the first said arm, a socket hinged to the last said arm, a pin rotatably mounted in the socket, a rest, means carried by the pin for hingedly supporting the rest, the arms, socket, pin and longitudinal axis of the 105 rest being in the same horizontal plane, the rest being designed to be rotated about the pin, and also about one of its end edges in a plane transverse to the first plane of rotation.

In witness whereof I have hereunto set my hand.

THOMAS DUNCAN McFARLANE.
